UNITED STATES PATENT OFFICE.

JOSIAH M. GRUMMAN, OF BROOKLYN, NEW YORK.

SURVEYOR'S CHAIN.

Specification of Letters Patent No. 23,680, dated April 19, 1859.

To all whom it may concern:

Be it known that I, JOSIAH M. GRUMMAN, of Brooklyn, county of Kings, and State of New York, have invented a new plan or 5 method of making Civil Engineers' and Surveyors' Chains and Attachments; and I do hereby declare that the following is a full and exact description thereof, reference being had to the accompanying drawings and 10 to the letters of reference marked thereon.

The nature of my invention consists of a more compact and correct form of making measuring chains and attachments.

The links, X, Fig. 8, are made of steel wire 15 tempered, of a peculiar form, which peculiarity consists of one eye being of an oval or egg shape—see W, Fig. 8,—while the other eye is round. This arrangement gives the following advantages. The oval eye has 20 length of wire enough to allow the smaller or round eye to be sprung into it thereby avoiding the use and error of irregular rings. The long slope or sharp end of the eye forms a shoulder, making a kink unusual and if a 25 kink forms it produces an elbow in the chain that will attract attention. Each eye has width enough to allow the chain to fold neatly and easily and each eye has a quick curve at the point of contact with the next 30 link which insures the contact in the same place every time the chain may be stretched out.

The forward end of the chain is a spring- 35 balance and spirit level combined, Figs. 1, 2 and 3. Fitting on the main tube A, is a second tube, B, sliding over it, with a clamp screw C, to fix it at any particular spot. When not in use, it is clamped over the bubble as a protection. A scale near the for- 40 ward end of the tube E shows the expansion and contraction of the chain for every ten degrees of the thermometer according to its length (the accompanying drawing is for a fifty feet chain). The scale runs from zero 45 to one hundred. The links of the chain are adjusted when made to be exact at fifty degrees, the mark for which on the scale is placed exactly (F,) the length of a link from the point of contact, Z, with the last 50 link of the chain. The spring balance L, M, is used to give an even tension to the chain and the same sag or curve Fig. 7 if measuring with the chain suspended. The scale Fig. 4 is marked in pound divisions or it

may be arranged to have two marks only, 55 one to draw to when the chain is suspended and the other when the chain lays on the ground. The spirit level D,—see Figs. 1, 3, and 6 for the arrangement—so adjusted by the screw I, R, (which is set in the tube A, 60 and riveted at R, so that it will turn in the tube without vertical motion yet passes through the plate P, on which the bubble rests with a fine thread raising or depressing it as it turns) that when the chain is 65 suspended at its proper tension, the two ends being on a horizontal line Fig. 7, the bubble will center as at D, Fig. 1. At the end of the tube next the chain is a spring catch V, attached to the tube by a small link U, Fig. 70 2, shaped like the figure 8 placed in a lateral position; by means of this catch the spring balance and level can be attached to any link of the chain at pleasure.

At the back end of the chain Figs. 9 and 75 10, attached to a steel bar a, is a thermometer c, subject to the same influences of heat and cold as the bar a. The thermometer c, slides into a metal tube or covering b, which is soldered fast to two small blocks h, h, 80 which are riveted to the bar a. At a short distance from the mouth of the tube b, is a small block d, riveted to the bar a which keeps the thermometer from any chance of falling from the tube of itself; it can be 85 taken out however by simply raising it when withdrawing it from the tube. Exactly the length of a link from the point of contact g, 90 with the first link of the chain is a fine line e, with a notch on each side, from which line starts the measurement.

To measure with the chain the person at the back end of the chain examines the thermometer previous to measuring and calls out the temperature which may be for in- 95 stance 70°. The person at the forward end then sets the slide B, so that the line G, coincides with the 70° mark on the scale E. The hindmost person see Fig. 7, now holds the chain, by means of a plummet and line 100 105 so that the mark e, is directly over the point he wishes to measure from, the other then pulls the balance to the adjusted mark and raises or lowers the chain until the bubble centers, when the two ends of the chain are 105 on the same horizontal line, then, keeping the balance still to the mark, drops his plummet from the mark G, and setting a peg in

the point indicated by the plummet moves on until the hindmost person comes to the peg when the same operation is repeated.

What I claim as my invention and desire 5 to secure by Letters Patent is,

1. The method of making civil-engineers and surveyors chains of a peculiar form of link as before described and shown.

2. The arrangement of spring balance and 10 level in the same tube or covering with the arrangements for adjusting as before described and shown.

3. The method of allowing for the variation of the temperature by a scale of variation 15 on the chain with the adjusting slide

and clamp, as before described and shown, so that the chain may be virtually shortened or lengthened to meet the temperature.

4. The use of the spring catch by means of which the balance and level is detached 20 from the end link and attached to any other link in the chain at the pleasure of the operator.

5. The method of attaching the thermometer to the end bar of the chain as before described and shown. 25

J. M. GRUMMAN.
